CLAIM

The ornamental design for a case for an electronic device, as shown and described.

DESCRIPTION

FIG. 1 is a top view of the case for an electronic device in accordance with a first embodiment;

FIG. 2 is a rear view thereof;

FIG. 3 is a left side view thereof;

FIG. 4 is a right side view thereof;

FIG. 5 is a bottom view thereof;

FIG. 6 is a front view thereof;

FIG. 7 is a front-right perspective view thereof;

FIG. 8 is a top view of the case for an electronic device in accordance with a second embodiment.

FIG. 9 is a rear view thereof;

FIG. 10 is a left side view thereof;

FIG. 11 is a right side view thereof;

FIG. 12 is a bottom view thereof;

FIG. 13 is a front view thereof; and,

FIG. 14 is a front-right perspective view thereof.

The broken lines depict portions of the case for an electronic device that form no part of the claimed design.

1 Claim, 8 Drawing Sheets
